SECURING MEANS FOR WEATHER STRIPS

Louis A. Macklanburg, Oklahoma City, Okla.

Application March 21, 1932. Serial No. 600,306

1 Claim. (Cl. 20—69)

This invention relates to improvements in weatherstripping; and, more particularly, to a structure designed to prevent the securing means from presenting an unsightly appearance and an obstruction detrimental to the proper operation of the strip.

Heretofore, with a few exceptions, the securing means in the form of nails or screws have presented heads that extend above the strip, resulting in inefficient operation and a projection on which articles of clothing could be caught.

The object of my invention is to provide a protecting flange extending above the head of the securing means, and at the same time, hold the strip securely in place.

Other objects will be disclosed in the specification and claim forming a part of my application.

In the drawing:

20 Figure 1 is a perspective showing the strip secured to a block; and

Figure 2 is a section taken on line 2—2 of Figure 1.

Referring to the drawing in which similar parts are designated with like numerals:

25 Numeral 3 designates a nailing strip secured to the runway 4 of a window by nails 5 and having a free edge 6. In the nailing strip 3 is

formed a series of projections 7 in the form of embossed circles surrounding openings 8 adapted to receive the nails 5. The spaces between the projections 7 and openings 8 are filled by the strip material and may be slightly depressed 60 below the plane of the remainder of the strip. This material forms a seat for the heads 9 of the nails 5, the heads 9 being small enough to be received within the embossed portion and thus be entirely protected and in turn a smooth 65 contour is presented. By having the openings 8 approximately the same size as the body of the nails 5, there is little or no lost motion, the embossed portions fitting closely against the heads 9 of the nails 5.

70 What I claim is:

A sheet metal weatherstrip having a part extending lengthwise thereof and adapted to be secured to a frame member, said part being substantially U-shaped in cross section and having brad receiving apertures spaced apart along the center thereof, said part being stamped to form annular beads concentric with and of greater diameter than said apertures and adapted to form with said part recessed seats for the 80 heads of brads used to secure said part to a frame member.

75 LOUIS A. MACKLANBURG.
